UNITED STATES PATENT OFFICE.

ANDREW ROY PEFFERS, OF AURORA, ILLINOIS, ASSIGNOR OF ONE-HALF TO FREDERICK C. SCHULTZ, OF CONGRESS PARK, ILLINOIS.

NUT-LOCK.

1,274,077.

Specification of Letters Patent.

Patented July 30, 1918.

Application filed May 21, 1917. Serial No. 169,816.

To all whom it may concern:

Be it known that I, ANDREW ROY PEFFERS, a citizen of the United States of America, and resident of Aurora, Kane county, Illinois, have invented a certain new and useful Improvement in Nut-Locks, of which the following is a specification.

My invention relates to nut-locks in general, but more particularly to those for use 10 on rail-joints.

Generally stated, the object of my invention is to provide a novel and improved form of nut-lock which will provide sufficient spring-pressure to prevent rotation of the 15 nuts, which can be cheaply manufactured and easily applied, and which will tend to insure the requisite certainty and reliability in use.

It is also an object to provide certain 20 details and features of construction and combinations tending to increase the general efficiency and desirability of a nut-lock of this particular character.

To the foregoing and other useful ends, 25 my invention consists in matters hereinafter set forth and claimed.

In the accompanying drawings:—

Figure 1 is a horizontal section of a rail-joint having a nut-lock embodying the 30 principles of my invention.

Fig. 2 is a side elevation of the structure of the rail-joint and nut-lock shown in Fig. 1.

Fig. 3 is a vertical section on line 3—3 in Fig. 2.

Fig. 4 is a perspective of the leaf-spring or resilient sheet-metal member involved in the construction of the nut-lock.

As thus illustrated, the rails A and B are arranged end to end and connected together 40 by splice-bars C and D and transverse bolts 1, 2, 3 and 4, in the usual and well-known manner. Preferably, the alternate bolts are turned with their heads in one direction, and the intermediate bolts are arranged with 45 their heads in the opposite direction, in the manner shown.

The leaf-spring E is made of resilient sheet-metal, such as steel properly tempered for the purpose, and is formed with upper 50 and lower flanges e, these flanges being parallel and extending nearly to the opposite ends of the spring. The end-portions of said spring, starting at about where the flanges e terminate, are bent outward, and 55 are provided with notches 5 to engage the

cylindric sides of the bolts. The middle portion of the spring is provided with a bolt-hole 6 disposed between the upper and lower flanges e, and the intermediate or body-portion of the spring is substantially straight and flat on the inner side thereof.

In use, these springs are preferably applied in the manner shown in Figs. 1, 2 and 3. As thus illustrated, one spring is held 65 in place by the head 7 of the bolt 2, against the outer side of the splice-bar D, this bolt extending through the bolt-hole 6 of said spring. The notches 5 of this spring engage the cylindric sides of the bolts 1 and 3, and are flexed inward against the splice-bar by the nuts 8 and 9 of these bolts. The notches at the ends of the spring provide points 10 which engage the inner sides of the nuts, each notch partially embracing 70 the cylindric bolt. The other spring, at the other side of the rail-joints, is clamped in place by the head 11 of the bolt 3, and the ends of this spring are engaged and flexed inward by the nuts 12 and 13 of the bolts 2 and 4, in a manner that will be readily understood. When the nuts 8 and 9 are tightened, the end-portions of the spring E at 75 this side of the rail-joint are flexed inward, and this gives the spring a tendency to bulge 80 or bow outward at the center, but this tendency is counteracted and prevented by the head 7 of the bolt 2, so that the middle portion of the spring is retained flatwise against the outer surface of the splice-bar. This 85 tendency on the part of the spring to bulge outward is also counteracted and prevented by the stiffening flanges e, as these flanges extend in planes practically at right angles to the plane of the body-portion of the 90 spring, so that flexing of the spring at the middle portion thereof is practically impossible. Thus the full pressure of the 95 resilient end-portions of the spring is effectively exerted against the inner sides of the nuts 8 and 9, and the same action takes place at the other side of the rail-joint when the nuts 12 and 13 are tightened, so that each bolt has its head utilized to clamp the middle portion of a spring in position against the outer surface of one of the splice-bars, and the nut of each bolt bears against the 100 resilient end of one of the springs. With this construction, the spring-pressure against the inner sides of the nuts is sufficient to 105

110

prevent a loosening of the bolts, the points 10 engaging the inner sides of the nuts and thereby preventing rotation of the latter except when forcibly turned with a wrench.

5 The bolt-holes 6 in the springs are preferably oblong, and extend longitudinally of the springs, and the holes in the splice-bars are of the same oval or oblong shape. The bolts, it will be seen, have short shank-portions 14 which are oval or oblong in cross-section to fit the oval holes in the springs and splice-bars, and with this arrangement the rotation of the nuts will not turn the bolts, as the bolts are held against rotation 15 by their oval shank-portions when the nuts are tightened or loosened.

What I claim as my invention is:—

1. A nut-lock for rail-joints, comprising a leaf-spring having out-turned ends to engage and be flexed inward by the nuts, when the bolts of the rail-joint are tightened, and having means including a stiffening formation to prevent the middle portion of said spring from bowing outward.

25 2. The structure of claim 1, in which said middle portion has a bolt-hole therein, so that a bolt of the rail-joint will hold the middle portion of the spring when the ends thereof are pressed inward.

30 3. The structure of claim 1, in which said formation comprises a longitudinal flange on said spring to stiffen it between the flexible end-portions thereof.

4. The structure of claim 1, in which said formation includes top and bottom longitudinal flanges on said spring.

5. The structure of claim 1, in which said formation includes upper and lower flanges on said spring, and in which the spring has 40 a bolt-hole between said flanges.

6. In a rail-joint, the combination of a splice-bar, bolts extending through the bar and rail, and a leaf-spring having a non-flexible middle portion clamped to the splice

bar by one bolt and having out-turned ends 45 flexed inward and clamped by two other bolts to the splice-bar.

7. In a rail-joint, the combination of a splice-bar, bolts extending through the bar and rail, and a leaf-spring having its middle portion clamped to the splice-bar by one bolt and having out-turned ends flexed inward and clamped by two other bolts to the splice-bar, in which said spring is directly engaged by the head of the one bolt and by 55 the nuts of the other bolts.

8. In a rail-joint, the combination of a splice-bar, bolts extending through the bar and rail, and a leaf-spring having its middle portion clamped to the splice-bar by one bolt and having out-turned ends flexed inward and clamped by two other bolts to the splice-bar, in which the ends of said spring are formed with notches to engage and partially embrace said other bolts, thereby also 65 providing the spring with points which engage the inner sides of the nuts.

9. A nut-lock comprising a sheet-metal spring having a notched end-portion forming sharp corners to engage the inner side 70 of the nut, and means to hold said spring in position.

10. The combination of rails and a splice-bar at each side thereof, bolts extending through said rails and bars, a leaf-spring at 75 one side held in place against one bar by the head of one bolt and having its ends pressed inward by nuts on other bolts, and a similar leaf-spring at the other side held in place by the head of one bolt and having its ends 80 pressed inward by nuts on other bolts, so that some of said bolts are each engaged at one end by the middle portion of one spring and at the opposite end by the end of another spring.

Signed by me at Chicago, Illinois, this 16th day of May, 1917.

ANDREW ROY PEFFERS.
